UNITED STATES PATENT OFFICE

1,920,367

ELECTRIC WATER CLOSET

John C. Duner, Chicago, Ill.

Application January 21, 1931. Serial No. 510,078

5 Claims. (Cl. 4-8)

This invention relates in general to water closets, and more particularly to devices of this character provided for use in railway cars and the like. A principal object of the present invention is the provision of a railway water closet having a dump pan and flushing valve mechanism electrically controlled and actuated.

Another important object of the invention is the provision of a railway water closet, the dumping or flushing of which may be readily prevented while the car is standing in a station and without requiring the porter or other attendant to enter the room or compartment for the purpose.

Another important object of the invention is the provision of a water closet for railway cars and the like which may be operated with minimum effort.

Another important object of the invention is the provision of an electric actuating and control means for a railway water closet of simple construction, the parts of which may be so arranged as to make frequent repair, replacement, or readjustment unnecessary.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a water closet embodying my present invention and showing the parts in normal position;

Fig. 2 is a view similar to Fig. 1 showing the action of the parts in dumping;

Fig. 3 is a diagrammatic wiring layout;

Fig. 4 is a front view of a water closet, parts being broken away and shown in section to disclose the features of construction, and

Fig. 5 is a detail of the contact devices.

A water closet shown on the drawings and in which the present invention is embodied comprises a metal stand or base 12, a ceramic bowl 13, flushing valve mechanism 14, and the usual dump pan 15. The particular and detailed construction of these several major parts need not here be set forth.

The dump pan is pivoted at 16 to swing down from the normal position shown in Fig. 1 to the dumping position shown in Fig. 2 and back to the normal position at each flushing of the toilet. A weight 17 is arranged at one end of the pivotal axis 16 of the dump pan to counterbalance it and normally support it in position to close the outlet 18 of the closet bowl. An arm 19 is fixed

at the opposite end of the axis 16 and this arm is provided with a pin 21 arranged in a slot 22 at the lower end of a vertically extending link 23 in turn connected at 24 with a main operating lever 25. The lever 25 at its left hand end (viewing Fig. 1) is attached to the valve operating mechanism generally indicated at 26. The opposite end of the lever is pivoted at 27 to a link 28 which extends down to a connection 29 with a link or arm 31 fixed for rotation with a gear 32.

The gear 32 is the operating member of a chain of gears adapted to be rotated by an electric motor indicated generally at 33 in a motor housing 34 secured upon a bracket 35 integral with the stand 12.

Flushing of the toilet is accomplished by the mere pressing of a button or closing of the switch to complete the electric circuit to the motor. The motor and its gearing are so constructed and arranged that a complete flushing operation occurs at a single rotation of the gear 32. The link 31 moves from the position shown in Fig. 1 to the position shown in Fig. 2 to dump the dump pan and open the flushing valve to deliver water to the closet. Thereafter further rotation of the gear 32 back to its normal position as shown in Fig. 1 arranges the toilet for subsequent use.

Electric power is delivered to the motor as will now be described, reference being had particularly to Figs. 3 and 5. Line wires 36 and 37 may be considered the source of electric power. The wire 37 is tapped in at 38 to one terminal of a switch 39. It leads from the terminal 38 to a fixed terminal 41 in the motor housing. A bridge member 42 is arranged to engage the terminal 41 and a second terminal 43 in turn connected by wires 44, 45 and 46 to one of the motor terminals.

The wire 36 is connected to the other motor terminal. The second terminal 47 of the switch 39 is connected by a wire 48 to the wire 45. The bridging member 42 is normally out of contact with the terminals 41 and 43. It consists of the contact bar 42 which is mounted upon and insulated from two springs 49 which serve to press the bridging member 42 upwardly.

A stud 51 is fixed in a collar 52 upon the shaft 53 of the gear 32 and after each dumping operation the stud 51 presses the bridge member 42 down out of contact with the pins or terminals 41 and 43 interrupting the current. When it is desired to flush the toilet, the switch 39 is closed and current then flows to the motor through wire 37 of switch 39, wires 48, 45, and 46 to the motor and back through wire 36 to the source.

Immediately upon the starting of the motor and the commencement of the flushing action, the post 51 moves out of engagement with the bridging member 42 and an operating circuit is completed. This circuit consists of wire 37 to post or contact 41, bridging member 42, post or contact 43, wires 44, 45, and 46 to the motor and thence back by wire 36 to the source.

A second switch 54 is, or may be provided in the circuit. The switch 39 is arranged adjacent the water closet and is the switch commonly used in the flushing. The switch 37 is, or may be arranged outside the lavatory and when opened by the porter or other train attendant, prevents flushing of the closet when the train is standing in the station.

The lever 25 may be provided, if desired, with a socket 55 at its end attached to the link 28 for the reception of a handle 56 to permit manual operation if the motor be disconnected. The pin 21 and its slot connection with the link 23 permits dumping of the dump pan by the lifting of the weight and without operation of the electrical mechanism. This last is provided in order to facilitate flushing and cleaning of the toilet in the yards.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A water closet, comprising a closet bowl, a dump pan normally closing the outlet of said bowl and adapted to swing to a dumping position, and electric means for moving said dump pan to flush said bowl. 80

2. A water closet, comprising a closet bowl, a dump pan normally closing the outlet of said bowl and adapted to swing to a dumping position, and electric means for moving said dump pan to flush said bowl and return said dump pan to sealing position after flushing. 85

3. A water closet, comprising a closet bowl, a dump pan normally closing the outlet of said bowl and pivoted to swing downwardly in flushing, an electric motor and connections between said motor and said dump pan for swinging said dump pan downwardly in dumping and returning said dump pan after flushing. 90

4. A water closet, comprising a closet bowl, a valve mechanism for supplying flushing water to said bowl, a dump pan for closing the outlet of said bowl and movable to dump in flushing, and an electric motor connected to said dump pan and to said valve mechanism for operating said dump pan and said valve mechanism in timed relation. 95 100

5. A water closet for railway cars and the like, comprising a closet bowl, a dump pan closing the outlet of said bowl and movable in flushing, an electric means for operating said dump pan, said electric means including a plurality of circuit closing devices, one arranged adjacent the water closet and the other at a point removed therefrom. 105
